PUNCH-BLOCK FOR HEADING-MACHINES.

1,012,341.

Specification of Letters Patent.

Patented Dec. 19, 1911.

Application filed January 18, 1911. Serial No. 603,295.

To all whom it may concern:

Be it known that I, ERNEST W. DUSTON, a citizen of the United States, residing at Waterbury, county of New Haven, State of Connecticut, have invented an Improvement in Punch-Blocks for Heading-Machines, of which the following is a specification.

This invention relates to machines for making bolts, screws and the like and has reference more particularly to machines for forming the heads of such articles.

The general object of the invention is to provide a machine having means whereby the punches, which are employed to upset and form the heads on the bolts, may be adjusted upon the punch carrier so as to bring the same into proper position and alinement.

The more particular objects of the invention, together with means whereby the same may be carried into effect, will best be understood from the following description of one form or embodiment thereof illustrated in the accompanying drawings forming a part of this specification.

In said drawings, Figure 1 is a front elevation of the punch head of a bolt heading machine, showing the punch carrier, punch blocks, and punches; Fig. 2 is a side elevation, partly in vertical section, of the parts shown in Fig. 1; Fig. 3 is a front elevation and Fig. 4 a plan view of one of the slides which carry the punch block.

12 denotes a punch head which is slidably mounted in suitable guides in the machine frame and is operated by suitable mechanism (not shown) to advance and retract the punches.

13 denotes a punch carrier which is slidably mounted in the punch head 12 and is operated by suitable mechanism (not shown) to shift the punches on the head 12 to bring any desired punch into operative position with respect to the die which holds the blank on which the head is to be formed. This die, the mechanism for actuating the punch head, and the mechanism for operating or shifting the punch carrier are not

shown herein as they form no part of the present invention and are familiar to those skilled in the art.

14 denotes punch blocks carrying heading punches 15, said punches being preferably detachable from the punch blocks and secured in place therein by suitable means, such as screws 16. In accordance with the present invention the punch blocks 14 are mounted on the punch carrier 13 for independent adjustment both longitudinally and laterally of the said punch carrier.

17 denotes slots in the punch carrier 13 in which are located slides 18, said slides being preferably formed with ribs 19 received in rabbets formed in the punch carrier adjacent the slots 17. The slides 18 are guided in the slots 17 and are movable therein longitudinally of the punch carrier 13 by means of adjusting screws 20, preferably in threaded engagement with the punch carrier 13 and rotatably connected with the slides 18 by means of pins 21 which engage grooves in the ends of said screws.

The slides 18 are formed with recesses 22 to receive bosses 23 formed on the punch blocks 14, said punch blocks being further pivotally secured to the slides 18 by means of bolts or screws 24. The punch blocks 14 are movable about their pivots to provide an adjustment transverse to the punch carrier 13. To effect this adjustment and hold the punch blocks in adjusted position the following means are provided.

25 denotes studs or lugs projecting from the punch carrier 13 and loosely received in recesses 26 formed in the punch blocks 14. Said punch blocks are provided at either side of the recesses 26 with adjusting screws 27 engaging at their ends the studs 25 or lugs 25. As will be seen by proper manipulation of the adjusting screws 27 the punch blocks 14 may be swung about their pivots irrespective of the positions of the slides 18, said screws 27 also acting to secure said punch blocks in adjusted position.

The slides 18 provide means whereby the punch blocks may be independently ad-

justed in a rectilinear direction longitudinally of the punch carrier 13, while the pivotal mounting of these blocks permits them to be independently adjusted transversely of said punch carrier. By virtue of these independent adjustments either or any punch block may be brought into proper position and alinement with respect to the die without affecting the adjusted position of the other punch block or blocks.

Having thus described my invention, I claim:

1. The combination with a punch carrier, of a plurality of punch blocks provided with heading punches mounted on said carrier and independently adjustable thereon.

2. The combination with a punch carrier, of a plurality of punch blocks provided with heading punches mounted on said carrier, said punch blocks being independently adjustable longitudinally of said carrier.

3. The combination with a punch carrier, of a plurality of punch blocks provided with heading punches mounted on said carrier, said punch blocks being independently adjustable transversely of said carrier.

4. The combination with a punch carrier, of a plurality of punch blocks provided with heading punches mounted on said carrier, said punch blocks being independently adjustable both transversely and longitudinally of said carrier.

5. The combination with a punch carrier, of a plurality of punch blocks mounted on said carrier, said punch blocks being independently pivoted to said carrier.

6. The combination with a punch head and a punch carrier movable on said head, of a slide on said carrier and movable longitudinally thereof, and a punch block provided with a heading punch adjustably connected to said slide.

7. The combination with a punch carrier, of a plurality of punch blocks provided with heading punches mounted on said carrier, said punch blocks being independently adjustable in a rectilinear direction longitudinally of said carrier.

8. The combination with a punch carrier, of a plurality of slides on said carrier and independently movable longitudinally thereof, and punch blocks provided with heading punches carried by said slides.

9. The combination with a punch head and a punch carrier movable on said head, of a slide on said carrier and movable longitudinally thereof, a punch block provided with a heading punch adjustably connected to said slide, and means to move said slide on said carrier.

10. The combination with a punch head and a punch carrier movable on said head, of a slide on said carrier and movable there-

on in a rectilinear direction, and a punch block provided with a heading punch adjustably connected to said slide.

11. The combination with a punch head and a punch carrier movable on said head, of a slide on said carrier and movable thereon in a rectilinear direction, means to move said slide on said carrier, and a punch block provided with a heading punch adjustably connected to said slide.

12. The combination with a punch head and a punch carrier mounted on said head, of a slide on said carrier and movable thereon in a rectilinear direction, an adjusting screw on said carrier and connected with said slide, and a punch block provided with a heading punch adjustably connected to said slide.

13. The combination with a punch head and a punch carrier, movable on said head, of a slide movable on said carrier, and a punch block provided with a heading punch pivoted to said slide.

14. The combination with a punch head and a punch carrier movable on said head, of a slide movable on said carrier, a punch block provided with a heading punch pivoted to said slide, and means to move said punch block on its pivot.

15. The combination with a punch head and a punch carrier, movable on said head, of a slide movable on said carrier, a punch block provided with a heading punch pivoted to said slide, and means to hold said punch block in adjusted position on its pivot.

16. The combination with a punch head and a punch carrier movable on said head, of a slide movable on said carrier, a punch block provided with a heading punch pivoted to said slide, and coöperating means on said punch block and carrier for adjusting said punch block on its pivot.

17. The combination with a punch carrier, of a slide movable on said carrier, a punch block pivoted to said slide and provided with an aperture, a stud projecting from said punch carrier and loosely received in said aperture, and adjusting screws carried by said punch block and engaging said stud.

18. The combination with a punch carrier, of a punch block pivotally mounted on said punch carrier and provided with an aperture, a stud projecting from said punch carrier and loosely received in said aperture, and adjusting screws for fixing the position of said stud in said aperture.

19. The combination with a punch carrier, of a punch block pivotally mounted on said punch carrier and provided with an aperture, a stud projecting from said punch carrier and loosely received in said aperture,

and adjusting screws carried by said punch block and engaging said stud for fixing the position of said stud in said aperture.

20. The combination with a punch carrier, 5 of a plurality of punch blocks independently pivoted to said carrier and provided with apertures, studs projecting from said punch carrier and loosely received in said aper-

tures, and adjusting screws for fixing the position of said studs in said apertures.

10

In testimony whereof I affix my signature in presence of two witnesses.

ERNEST W. DUSTON.
